His Attorney.

UNITED STATES PATENT OFFICE

WILLIAM C. ROE, OF ELYRIA, OHIO, ASSIGNOR TO TELKOR, INC., OF ELYRIA, OHIO, A CORPORATION OF OHIO

PENDULUM

Application filed May 18, 1929. Serial No. 384,219.

My invention relates to pendulums and relates more particularly to pendulums adapted to control the escapement of a clock mechanism. Although it is well known that clock mechanisms employing pendulums to regulate the rate of escapement of the chronograph mechanism are susceptible of closer regulation of their time controlling function when the pendulum oscillates at a relatively slow rate, such pendulums have heretofore been necessarily of considerable length so that a pendulum oscillating at a period of one second is regarded to be over a yard long. This necessitates the provision of greatly elongated cabinets for the clock mechanisms which are only useful for enclosing the pendulum.

An object of my invention, therefore, is the provision of a pendulum of relatively long periodicity for its overall length.

The drawings illustrate an embodiment of my invention wherein:

Fig. 1 is a front elevational view of a pendulum mechanism embodying the principles of my invention, an alternate position of the parts being indicated by dotted lines.

Fig. 2 is a side elevational view thereof.

Referring to the drawings, at 1 I show a support for a pendulum which comprises a pendant resilient reed 2 supporting at its lower end a connector 3 affixed thereto, and an upstanding reed 4 rigidly secured at one end to the connector 3 and at its other upper end supporting a weight 5.

The support 1 may take various forms, but I preferably clamp the reed 2 between parallel wings 7 and 8 of a sheet metal stamping, having terminal flanges 9 by which the pendulum support may be rigidly affixed to the form 10 of a clock mechanism.

In the embodiment illustrated, the pendant reed 2 comprises a pair of flat steel springs disposed in relatively edgewise parallel relation throughout their lengths. The reed 4, however, in the embodiment illustrated, comprises a single flat steel spring carrying at its upper end the weight 5 which is affixed to the spring 4 in any suitable way, and preferably comprises a connecting tongue 11 slotted to receive the end of the spring 12 between the

bifurcated portions of the tongue. This construction insures that the effect of the weight will not create a localized bending stress on the end of the spring 4 to either break it or cause segmental vibration of the reed 4.

As illustrated, the upstanding spring 4 is disposed edgewise between and in parallel relation with the twin springs comprising the reed 2 and the effect of this arrangement is to permit oscillation of the weight 5 between the adjacent edges of the twin springs 2 as indicated by the solid line and dotted line illustrations of alternating positions of the weight illustrated in Fig. 1.

At 13 a pair of forks or an escapement controlling lever 14 are shown, the said forks being disposed on opposite sides of at least one of the springs 2 at an intermediate portion of its length.

In operation the weight 5 oscillates to the alternating extreme positions indicated in Fig. 1 and during such oscillation the lower ends of the reeds carrying the connector 3, take alternate positions as indicated by dotted and solid lines in Fig. 1.

Such a pendulum will oscillate at a very low periodicity, this being particularly true when the reed springs 2 and 4 are each made very thin; and, when, as preferred, the cross sectional area of the spring 4 throughout substantially its entire length, is equal to the cross sectional areas of the springs making up the reed 2.

Having thus described my invention I am aware that numerous and extensive departures may be made from the embodiment herein illustrated and described but without departing from the spirit of my invention.

I claim:

1. A pendulum comprising in combination with a fixed support, a reed pendant by an end therefrom, a second reed secured at a freely oscillatable portion of the first reed, extending upstandingly therefrom and a weight carried by the second reed remotely of its supported end.

2. A pendulum comprising, in combination with a fixed support, a reed pendant by an end therefrom, a second reed secured at a freely oscillatable portion of the first reed,

extending upstandingly therefrom and a weight carried by the second reed remotely of its supported end, one of said reeds comprising a pair of parallel springs, the other 5 of said reeds extending in parallel relation between said springs.

3. A pendulum comprising, in combination with a fixed support, a reed pendant by an end therefrom, a second reed secured at a 10 freely oscillatable portion of the first reed, extending upstandingly therefrom and a weight carried by the second reed remotely of its supported end, one of said reeds comprising a pair of parallel springs, the other 15 of said reeds extending in parallel relation between said springs, all of said reeds comprising strips of flat spring material normally disposed in parallel edgewise relation.

In testimony whereof I hereunto affix my 20 signature this 10th day of May, 1929.

WILLIAM C. ROE.
